FRANK MICHAEL LEWIS, OF BRIGHTON, ENGLAND, ASSIGNOR TO GENERAL ELECTRIC COMPANY, A CORPORATION OF NEW YORK.

PROCESS FOR OPERATING ELECTRIC-ARC LAMPS IN SERIES.

No. 894,167.

Specification of Letters Patent.

Patented July 21, 1908.

Original application filed November 21, 1904, Serial No. 293,028. Divided and this application filed January 20, 1908, Serial No. 411,879.

To all whom it may concern:

Be it known that I, FRANK MICHAEL LEWIS, a subject of the King of Great Britain, and resident of Prestonville Terrace, Brighton, England, have invented a new and useful Process for Operating Electric-Arc Lamps in Series, of which the following is a specification.

The process of regulating arc lamps in which shunt coils are used is well understood. As the arc grows longer, more and more current is diverted to the shunt coil until, finally, the shunt coil is energized sufficiently to bring into play a force which, acting on the carbon controlling mechanism, restores the arc to its fixed and normal length. The regulation is effected by playing the shunt against the series coil. If such lamps are used in series, each lamp maintains its arc-length constant irrespective of the other lamps. Practically speaking the regulation of each lamp is self-contained and no one lamp in the series acts to control the arc length of any other lamp. The arcs are not kept of the same fixed length by any true process of synchronization as between different lamps. Each lamp stands on its own bottom as if there were no other lamps in circuit. In my process all this is different.

In accordance with my process, I take an electric arc lamp in which the regulation is effected by a series coil only, that is to say in which there is no shunt regulating coil. I mount two or more such lamps in series in an electric circuit. In order that the arcs in the several lamps in the series, after the arcs have once been struck, may each be of the same length, no matter what instant of time is selected for comparison, it is clearly necessary, carbon consumption being uniform, that the armatures which control the carbon controlling mechanisms or clutches shall, at any instant, be in the same position in each lamp. Now I attain the synchronization of the armatures governing the carbon controlling mechanisms, in each of the lamps of the series, in accordance with my process, not by a force self-contained in the lamp itself, which acts irrespective of the other lamps and which keeps each arc of a fixed length, irrespective of the other arcs. On the contrary I attain this synchronization of armatures by having those lamps of the series, which have their armatures in the normal

or proper position for the instant of time we are considering, determine, by means of the arc-length which goes with this armature position, such a current flow in the circuit as will exercise an adequate differential restoring force upon the armature of the lamp which is out of its proper position. The armature out of position will thus be pulled into position; its position will be synchronized with that of the other armatures.

Stated more specifically, I impress a constant electrical potential upon the circuit in which the lamps, having series regulating coils only, are mounted in series and I so construct the armature and coil of each lamp that current strengths which differ essentially are required to equilibrate the armatures in each of the different positions it occupies in its travel. It will be plain then that if all the lamps of the series except one, say, have their armatures in the same position and have each a corresponding equal arc-length that the constant electrical potential impressed upon the series circuit will cause the flow of a current sufficient in quantity to keep these armatures in the positions which they occupy. It is equally plain that the current flowing in the coil of the lamp whose armature is out of position will be either essentially greater or essentially less than necessary to hold the armature in its position. There will thus be exercised upon the abnormally positioned armature a differential restoring force either in the form of unbalanced mechanical pressure or of unbalanced electromagnetic pull which will bring it back into position.

When I have said that the different positions of the armature required equilibrating current strengths which are essentially different, I mean that the difference in equilibrating current strengths between any two adjacent positions of the armature is sufficient to cause the differential restoring force called into play to be adequate to do the work of synchronizing or restoring to its proper position the armature which is out of position. Since I may employ an armature the attraction on which varies with the square of the current, it will be seen that that current may be essentially different in the sense in which I use the term and yet not differ greatly as shown by ammeter readings. On the other hand, it is possible for the currents

corresponding to different armature positions to differ somewhat and yet, with the type of armature used, it may happen that the differential force brought into play is insufficient to synchronize the displaced armature; such current-strengths, under the terminology which I employ, would not differ essentially.

In executing my process I may so arrange matters that the greatest current will flow in the group of lamps when the arcs have just been struck and that the current grows gradually less as the arcs burn and the armatures move to make up for the consumption of carbon. But since in a constant potential system less current flow corresponds to a greater arc-length, it is plain that arcs in the several lamps of the group, in my process, while they are all caused to be of equal length at any given instant of time, are also caused to all grow gradually longer as the initial period of arc-striking is departed from. Considering the group of lamps in the series circuit, we find a group of arcs each with a given arc length at any given moment and, after the lapse of a little time, each with a little longer arc. There is, as it were, a group variation of arc-length. What is more when the arc of any one lamp of the group, by the described operation, grows longer than can be maintained, I prefer to cause the circuit to be broken for the whole group of lamps, so that each lamp, of the group feeds forward its carbon until the carbons contact and the coils strike all the arcs anew. This is striking by groups only, as it were, I effect by a regulation restarter which will be described later on.

In order that the current strengths for different positions of the armature may differ essentially and may thus call into play an adequate restoring force to synchronize any displaced armature, I may use electric arc lamps of radically different types, it being understood however that my process is confined to the operation in series of arc lamps with series regulating coils only. Thus I may use a type of lamp in which the electromagnetic pull of the coil upon the armature is made to vary in the different armature positions. Or I may use types of lamps in which the mechanical pull of the armature against the coil is made to vary in its different positions. These results I can also bring about by a variety of mechanisms. It will be necessary here merely to describe a single lamp so that the operation of my process may be understood. The lamp which I select will be of the type in which the mechanical pull of the armature against the coil is made to change in its travel.

In the drawings:—Figure 1 is a side elevation, partly in section, showing a lamp embodying my invention after the arc has just been struck; Fig. 2 is a similar view show-

ing the parts after the lamp has been burning for some time; and Fig. 3 is a diagrammatic view of three of these lamps in series across constant potential mains.

I have shown my lamp with a series regulating coil 5 only. There is no shunt coil. The core 1 has pivoted to it a clutch 6 which embraces a carbon 7 so that as the core is pulled up in the solenoid, the clutch tilts and grips the carbon 7 and raises it to strike the arc. Fastened to the lamp frame is a pivot 50 upon which I mount a lever 2 connected, at one end, to the core 1 by a link 8 and, at the other end, to a dash pot 9 for the purpose of steadyng the movement. Rigidly connected with the lever 2 is an arm 3, at right angles to the lever 2, carrying a weight 4, the arm and weight constituting a bob.

It will be seen that when the core 1 is in its highest position, after the arc has just been struck, the bob is to the right of the center and exercises a force tending to depress the core. In effect the core is made heavier by the bob in its highest position. When the bob is vertical, it exercises no force upon the lever 2 and the core 1 exercises a downward pull determined by its weight and that of its attached parts. When the core is in its lower position and the bob is to the left of the vertical, as in Fig. 2, it exercises a pressure tending to raise the core. This, in effect, makes the downward pull of the core less than that corresponding to its weight and that of its attached parts. In other words the action of the bob, within the limits of the travel of the core, is to make the core heavier the higher up it is drawn and lighter the lower down it falls. The mechanical pull of the armature against the coil grows greater as the position is approached in which the arc has just been struck. This means that the higher the core position, the stronger the current in the solenoid necessary to hold the core in that position. For every position of the core there is a corresponding but essential different equilibrating strength of current. The differential force called into play upon any armature which is out of position is therefore sufficient to synchronize it.

The construction of electric lamp which I employ is clearly no feature of my process. I may use lamps of radically different designs and types so long as they regulate by the series coil only. On the other hand it is essential, in my process, to have the series circuit carry a current of constant potential as distinguished from a current of constant magnitude. Such constant-potential current acting on the group of lamps is made to determine the flow of essentially different current strengths in the circuit depending upon the mean arc-length, at the moment under consideration, in the group of lamps. This, in turn, causes the production of a differential restoring force upon any lamp in the

group whose armature happens to be out of the then mean position. When the arc length of any lamp in the group has reached a length which it is initially determined no lamp in the group shall exceed, the circuit of the group is broken, all the carbons of all the lamps run together, the arcs are again struck and the process takes place anew. Or looking at the arcs only of the group of lamps, we find, when the current is first turned on, the arcs are struck and all arcs of the group have the same length. This group-length, in the process of burning, gradually grows longer. If any lamp of the group, at any moment, have an arc-length which differs from what I have termed the group-length, a differential restoring force will be generated to bring the arc-length in question back to the group arc-length. After a sufficient time, some one of the arc-lengths of the group will have attained a length longer than can be maintained. Immediately all the arcs are extinguished, all the carbons run together, and all the arcs are struck afresh, so that the described process may be repeated.

It remains to describe the regulation re-starter by which the lamps of the group have their arcs simultaneously struck when a single arc grows too long. The lever 2 is extended to the left in a prolongation 10, carrying a pin 15, working in a slotted link 16, attached to the keeper 13, of an electromagnet 14, in the lamp circuit. The slot in the link is of sufficient length for a certain amount of regulation of the arc by means of the regulating solenoid 5, to take place, without any movement of the keeper, the pin 15 playing between the extremities of the slot 16 during such regulation.

Let us assume that the parts are in the position which they occupy when no current is on, that is to say with the carbons together, the clutches resting on their stops, the lever 2 lying inclined with the core well below the solenoid and the keeper hanging above the electromagnet with the pin at the top of the slot. When the current is now switched on, it traverses the pair of carbons, the solenoid 5 and the electromagnet 14. The core is pulled upwards, its end of the rocking lever is raised, the clutch is pulled up and the arc is struck. At the same time the other end of the rocking lever is depressed, the keeper 13 is brought within pulling distance of the electromagnet 14 and is attracted and held by the latter. The distance through which the keeper moves is however smaller than the distance through which the pin on the rocking lever moves, so that the pin descends some distance in the slot and the keeper no longer hangs from its limb of the lever.

What I might term the group regulation of arc-length now takes place; the cores drop gradually lower and the pins 15 rise in the slots 16. If, at any moment, any given arc

of the group is not of the same length as the other arcs, the differential restoring force will be generated. But, after a while, the group-length of the arc will have gradually grown longer and longer, by which time the pin 15 in one of the lamps will have reached the head of the slot 16. Thereupon the core in that lamp can drop no further but remains stationary. The carbon can no longer feed and the arc in that lamp gets so long as to finally break. This breaks the group circuit. The solenoids and electromagnets of the several lamps are no longer traversed by current, so that the core and keeper in each lamp of the group is released, the core dropping and bringing the clutch into contact with a stop so that the upper carbon drops into contact with the lower carbon. The circuit of the group having thus been re-established, the arcs are all struck anew and the cycle of operation is repeated.

Although I have spoken of the fact that the current strength and the group arc-length vary in my process, and while it is true that the variation must be sufficient to produce the results stated herein, it is equally true, as has been abundantly demonstrated in practice, that the variation referred to is not sufficient to be noticeable by the user in the matter of the steadiness of the illumination or the like.

This application is a division of my application No. 233,628, filed November 21, 1904.

I claim,

1. The process of operating a group of electric arc lamps, each having a series regulating coil but no shunt coil, which consists in connecting them in series circuit, impressing a constant potential upon the circuit, and generating a differential restoring force to bring to the mean position the armature of any lamp whose position is displaced with reference to that of the other lamps of the group, substantially as described.

2. The process of operating a group of electric arc lamps, each having a series regulating coil but no shunt coil, which consists in connecting them in series circuit, impressing a constant potential upon the circuit to determine at each instant a current-flow corresponding to the mean arc-length of the group at that instant, and causing the group arc-length and with it the current strength to be changed essentially in the operation of burning, whereby a differential restoring force is generated to return to the mean position the displaced armature of any lamp of the group, substantially as described.

3. The process of operating a group of electric arc lamps, each having a series regulating coil but no shunt coil, which consists in connecting them in series circuit, impressing a constant potential upon the circuit, generating a differential restoring force to bring to the mean position the displaced armature

of any lamp in the group, and breaking the circuit of the group, to cause all the lamps to feed and strike their arcs anew, when any given arc of the group has grown longer than 5 a predetermined maximum, substantially as described.

4. The process of maintaining a mean arc length in a group of electric arc lamps which consists in energizing the lamps in series by a 10 constant potential, and causing a differential restoring force to lengthen or shorten the arc of any lamp by and in opposition to the deviation of the arc from the mean length.

5. The process of operating a group of arc

lamps in series which consists in impressing 15 a constant potential on the circuit and causing the arc length of each of the lamps in series to vary in unison from moment to moment to thereby gradually change the current flow, substantially as described.

In testimony whereof I have signed my name to this specification in the presence of two subscribing witnesses.

FRANK MICHAEL LEWIS.
